UNITED STATES PATENT OFFICE.

FREDERICK EISENHUT, OF NEWARK, NEW JERSEY.

DETACHABLE MASSAGING DEVICE FOR BRUSHES AND THE LIKE.

1,175,249.

Specification of Letters Patent. Patented Mar. 14, 1916.

Application filed August 20, 1915. Serial No. 46,429.

To all whom it may concern:

Be it known that I, FREDERICK EISENHUT, a citizen of the United States, residing at Newark, in the county of Essex and State of New Jersey, have invented certain new and useful Improvements in Detachable Massaging Devices for Brushes and the like; and I do hereby declare the following to be a full, clear, and exact description of the invention, such as will enable others skilled in the art to which it appertains to make and use the same, reference being had to the accompanying drawings, and to characters of reference marked thereon, which form a part of this specification.

This invention has reference, generally, to improvements in massaging devices; and, the present invention relates, more particularly, to a novel means for the attachment of a massaging device to the handle of a shaving brush, or the like.

The present invention, therefore, has for its principal object to provide a novel and simply-constructed massaging device for brushes, and especially for shaving brushes; and, the invention has for its further object to provide a novel and simple means for detachably securing a massaging device to the handle of a brush, with a view of easily and quickly detaching the massaging device when it is desired to remove the same for cleansing purposes, and to again easily and quickly secure the massaging device in its operative position upon the handle of the brush, after it has been cleansed.

The invention has for its further object to provide in connection with a detachable massaging device for shaving brushes, a guard in connection therewith which will prevent the possibility of soap and water getting upon the massaging fingers of the device, and thereby contaminating the same with foreign matter, or destroying the usefulness of the massaging device.

Other objects of the present invention not at this time more particularly enumerated will be clearly understood from the following detailed description of the present invention.

With the various objects of the present invention in view, the said invention consists, primarily, in the novel detachable massaging device for brushes hereinafter set forth; and, the invention consists, fur-

thermore, in the novel arrangements and combinations of the various devices and parts, as well as in the details of the construction of the said parts, all of which will be more fully described in the following specification, and then finally embodied in the clauses of the claims which are appended to and which form an essential part of the said specification.

The invention is clearly illustrated in the accompanying drawings, in which:

Figure 1 is a side elevation of a massaging device and a shaving brush to the handle of which said massaging device is attached, and all made according to and representing one embodiment of the principles of the present invention. Fig. 2 is a top view of the detachable massaging device; Fig. 3 is a longitudinal vertical section of the same, said section being taken on line 3—3 in said Fig. 2; and Fig. 4 is a transverse vertical section of the massaging device, said section being taken on line 4—4 in said Fig. 2, looking in the direction of the arrow *x*. Fig. 5 is a face view of a split clamping ring employed with the various parts of the massaging device, said view being on a larger scale.

Similar characters of reference are employed in the said above described view, to indicate corresponding parts.

Referring now to the several figures of the drawings, the reference-character 1 indicates a suitable brush, such as a shaving brush, and which is provided with the usual handle, as 2. The massaging device, which is detachably mounted upon the said handle, is indicated by the reference-character 3, and the same consists, essentially, of a suitable base, as 4, which may be made of wood, or any other suitable material, and is preferably made in the form of a button. The front face of this button is usually made flat, as at 5, and is surrounded by a suitably rounded and chamfered marginal edge, as 6. The front face of this button is made with a nut-receiving depression or recess, as 7, and with a hole or perforation 8 in communication with said depression or recess. Sprung over this button so as to be mounted upon the back of said button, in the manner illustrated more particularly in Fig. 3 of the drawings, is a flexible cap-like element, as 9, made of rubber or other

analogous material, the back of said element being made with an open portion 10, and its main body-portion 11 being made with a multiplicity of massaging fingers, as 12. Mounted in said receiving depression or recess 7 is a nut 13, into which is secured a screw-threaded shank 14, passing through the opening 10 in the cap-like element 9 and through the hole or perforation 8 in the button, as 4, said shank 14 being of the proper length, and having suitably affixed upon its opposite end-portion, a retaining plate or member, as 15. Upon the said shank 14 is a lock-nut 16, and between this nut 16 and the back of the button 4, and also mounted upon said shank 14, is the inwardly pressed central portion 18 of a flexible guard, as 17, said guard being made of rubber, or analogous material, and its surrounding 20 marginal portion 19 being molded in a manner so as to extend in a forward direction and securely embrace the rounded marginal portion of the said cap-like element 9, so as to provide a substantially tight closure, which will prevent soap and water from lodging in the nut-receiving depression or recess 7, and surround the connecting parts, whereby the device might be rendered unsanitary and unsightly, as will be clearly 30 evident. Also mounted upon the shank 14 and located between the lock-nut 16 and the retaining plate 15 is a flexible guard-member or element, as 20, made of rubber or other analogous material.

In order to detachably secure the massaging device just described upon the handle 2 of the brush 1, a split clamping ring, as 21, is employed, which is slipped over the end of the handle, into the position indicated in Fig. 1 of the drawings. As shown, more especially in Fig. 5, this clamping ring 21 is provided upon its split end-portions 22 and 23 with screw-receiving sockets as 24 and 25, respectively, the sockets 24 being internally screw-threaded, and the sockets 25 having smooth bores, for the reception of suitably constructed tightening or binding screws 26. As is further shown in said Fig. 5, the said end-portions 22 and 50 23 of the split ring 21 are also cut away, as at 27, to suitably and firmly embrace the flexible guard-member or element 20, and to retain the clamping ring in its properly aligned relation with the other elements of the massaging device, prior to arranging the latter upon the handle of the brush and before securing the massaging device in its rigidly fixed relation upon said handle by tightening the said screws 26, as will be 55 clearly evident.

Of course I am aware that some changes may be made in the general arrangements and combinations of the various devices and parts, as well as in the details of the construction of the said parts, without depart-

ing from the scope of the present invention as set forth in the foregoing specification and as defined in the clauses of the claim which are appended to the said specification. Hence, I do not limit my present invention to the exact arrangements and combinations of the various devices and parts as described in the said specification, nor do I confine myself to the exact details of the construction of the said parts, as illustrated in the accompanying drawings. 75

I claim:

1. A massaging device comprising a massaging element provided with massaging members, a flexible guard mounted upon the back of said element, said guard having a forwardly extending marginal portion embracing the marginal portion of the massaging element, and means connected with said massaging element for detachably securing said massaging device to the handle of a brush or the like. 80

2. A massaging device comprising an element provided with massaging members, a flexible guard mounted upon said element, and means connected with said element for detachably securing said massaging device to the handle of a brush or the like, consisting of a shank extending from said element, a retaining member connected with said shank, a split clamping ring provided with screw-receiving sockets, and tightening screws in said sockets. 95

3. A massaging device comprising a button-like base, a flexible cap-like element arranged upon the back of said base, with its marginal edge sprung over and in retaining engagement with the marginal edge of said base, said element being provided with massaging members, and means connected with said base for detachably securing said massaging device to the handle of a brush or the like. 100

4. A massaging device comprising a button-like base, a flexible cap-like element arranged upon the back of said base, with its marginal edge sprung over and in retaining engagement with the marginal edge of said base, said element being provided with massaging members, and means connected with said base for detachably securing said massaging device to the handle of a brush or the like, consisting of a shank extending from said base, a retaining member connected with said shank, a split clamping ring provided with screw-receiving sockets, and tightening screws in said sockets. 110 115

5. A massaging device comprising a button-like base, a flexible cap-like element arranged upon the back of said base, with its marginal edge sprung over and in retaining engagement with the marginal edge of said base, said element being provided with massaging members, a flexible guard mounted upon said element and means con- 120 125 130

nected with said base for detachably securing said massaging device to the handle of a brush or the like.

6. A massaging device comprising a button-like base, a flexible cap-like element arranged upon the back of said base, with its marginal edge sprung over and in retaining engagement with the marginal edge of said base, said element being provided 10 with massaging members, a flexible guard mounted upon said element, and means connected with said base for detachably securing said massaging device to the handle of a brush or the like, consisting of a shank extending from said base, a retaining member connected with said shank, a split clamping ring provided with screw-receiving sockets, and tightening screws in said sockets.

7. A massaging device comprising a button-like base provided in one of its faces with a nut-receiving recess and having a hole leading from the opposite face of said base to said recess, a nut in said recess, a flexible cap-like element sprung over said base, said element being provided with massaging members, a screw-threaded shank extending through said element and said base and screwed into said nut, a lock-nut upon said shank, and a flexible guard-member 25 also mounted upon said shank, a retaining member connected with said shank, and a split clamping ring in engagement with said retaining member for detachably securing said massaging device to the handle of a brush or the like, the split end-portions of said clamping ring being provided with screw-receiving sockets, tightening screws in said sockets, the said end-portions of the said clamping ring being provided with cut away 30 portions adapted to receive and embrace the said flexible guard-member, and a second flexible guard mounted upon said shank between said lock-nut and the said button-like base, said last-mentioned guard embracing a portion of the massaging member-provided element, substantially as and for the 35 purposes set forth.

ing provided with cut away portions 40 adapted to receive and embrace the said flexible guard-member.

8. A massaging device comprising a button-like base provided in one of its faces with a nut-receiving recess and having a hole leading from the opposite face of said base to said recess, a nut in said recess, a flexible cap-like element sprung over said base, said element being provided with massaging members, a screw-threaded shank extending through said element and said base and screwed into said nut, a lock-nut upon said shank, and a flexible guard-member also mounted upon said shank, a retaining member connected with said shank, and a split clamping ring in engagement with said retaining member for detachably securing said massaging device to the handle of a brush or the like, the split end-portions of said clamping ring being provided with screw-receiving sockets, tightening screws in said sockets, the said end-portions of the said clamping ring being provided with cut away 45 portions adapted to receive and embrace the said flexible guard-member, and a second 50 flexible guard mounted upon said shank between said lock-nut and the said button-like base, said last-mentioned guard embracing a portion of the massaging member-provided element, substantially as and for the 55 purposes set forth.

In testimony, that I claim the invention set forth above I have hereunto set my hand this 18th day of August, 1915.

FREDERICK EISENHUT.
